UNITED STATES PATENT OFFICE

THOMAS H. IRRELAND, OF ROCKVILLE CENTER, NEW YORK

SYSTEM FOR DRYING PAPER AND TEXTILES AND THE LIKE

Application filed March 1, 1930. Serial No. 91,920.

This invention relates to a system for drying paper, textiles and the like and more particularly to a steam and condensation system adapted for arrangement in connection with any desired heating or drying unit for almost any desired use.

One of the primary objects of my invention is to provide a system for the continuous circulation of steam through a series of steam circuits arranged for drying textiles, papers, etc., in such a manner as to gradually raise the temperature of the material being dried from its point of entry to its point of exit and in such a manner that the material will be gradually dried at each succeeding station.

Another object is to provide a system of the character described wherein a rapid and continuous circulation of steam is maintained through a series of drying units while maintaining a constant or substantially constant temperature at each unit and a constant differential temperature between succeeding units.

Still another object is to provide a system wherein the steam or other condensable vapor is continuously circulated through a series of drying units or the like and whereby the condensate and accumulated air may be quickly and effectively removed.

A still further object is to provide a system wherein a rapid and continuous circulation of condensable heating medium may be maintained in two or more parallel series of circuits and wherein condensation of the vapor and accumulated air will be quickly and continuously removed.

Further objects include the provision of a system adapted to utilize steam or other high temperature condensable vapor exhausted from other apparatus or from a high pressure turbine or boiler or from both such sources as desired, the provision of an effective and simple system of high efficiency, the provision of a system which is automatic in its operation, and the provision of many other advantages and novelties of construction and operation which should become apparent from the description and claims and from the drawings in which:

Figs. 1 and 2 are diagrammatic top plan

and side elevational views of a system of drying units arranged in accordance with one form of my invention, and

Fig. 3 is a diagrammatic view of one arrangement of condensing apparatus suitable for connection with the drying units shown in Figs. 1 and 2.

The invention has been illustrated in connection with the usual drying cylinders or rolls of a paper or textile machine dryer wherein several series or banks of rolls or cylinders are provided and over which the textile material or paper is carried in order to dry it. Usually the sheets of paper or textile material are entered at what is known as the wet end of the dryer, which is maintained at a low temperature, and carried over and between rolls of successively higher temperatures to the opposite end of the series known as the dry end, where it is removed and disposed of as desired. The number of rolls required for each series and the number of series are dependent upon such factors as thickness of material, amount of moisture carried and the speed of travel, the temperatures maintained, etc., and it may be desirable, as is well known, to have the temperature gradient gradually increase from the wet to the dry end.

In apparatus of this character heretofore known and utilized, the temperatures maintained in the various cylinders have never been controlled in any definite manner and have been allowed to fluctuate even under constant external conditions, and no means has ever been provided whereby a substantially constant and predetermined differential temperature could be maintained between successive rolls in order that the material to be dried would be gradually heated to dry gradually and thoroughly.

Furthermore, the capacity of drying apparatus has been quite limited, largely due to the inefficiencies above noted, and a greater number of drying rolls or cylinders required than would be necessary in a system maintaining constant temperatures or constant differential temperatures throughout the several units of each series. It also often happened that non-condensable gases, i. e., air, became

trapped in the various cylinders or units and prevented such cylinders from being heated to the temperatures desired, if at all, but with my invention such defects are entirely obviated.

Referring to Fig. 2, two series of drying cylinders, rolls or units 1, 2, 3, 4 and 5 and 6, 7, 8, 9 and 10 are connected by means of pipes 11, 12, 13, 14 and 15 and 11', 12', 13', 14' and 15' respectively, to a common steam supply manifold 16 which may be connected through a pipe 17 to a turbine or steam engine exhaust or to any other source of steam or high temperature condensable vapor supply and may be connected to several sources if desired. The rolls of both series are of any preferred construction and may be arranged in any suitable manner, as will be readily understood, and since their construction forms no part of the present invention they have not been shown except diagrammatically and will not be further described except to say that they are adapted to receive steam under relatively high pressure within their interiors and are usually adapted to be rotatively driven by mechanism not shown. The paper or other textile material is entered on the rolls at the wet end, which for the purpose of illustration may be designated as the right end of Figs. 1 and 2 and carried successively and alternately over and under top and bottom rolls, or over and under alternate rolls of each series to the dry end at the left, where it is removed for disposal as desired.

The rolls of each series are connected in series by pipes 18, 19, 20, and 21 and 22, 23, 24 and 25 respectively, so that each roll of each series will receive steam which has passed through its preceding roll. The exhaust parts of the rolls at the wet end of each series are connected by means of pipes 26 and 27 respectively, for the passage of exhaust steam to an exhaust or condensation manifold 28 to which pipes 29, 29', 30, 30', 31, 31', 32 and 32' are also connected for removal of condensation from the piping connecting the several rolls of each series, as will later appear more clearly. The condensation return line or manifold 28 is also connected through a suitable line including valves 33, 33', combination thermostat and float traps 34 and sediment separators 35 to the bottom of one end of the steam manifold 16 at the wet end as shown, or at the dry end, or at any low point in the line, as desired, for the removal of any condensation accumulating therein, and the pipes 29 to 32' inclusive are each adapted to drain condensation from the several exhaust steam lines connecting the rolls of each series and the steam supply lines 11 to 15' inclusive connecting the manifold or header 16 with the several rolls through valves 36 and 37 in each drain

line, a sediment separator or strainer 38 and a combination thermostat and float trap valve 39. The above mentioned thermostat and float trap valves are well known on the market and are for the purpose of permitting condensation and air or other gases to pass them while preventing steam from passing. They are thermostatically operated and may be bought for varying capacities and other conditions of practice. For the valves 34 I prefer a small size of trap valve and for the valves 39 a large size of trap valve, although varying capacities and conditions may dictate other specifications. Each exhaust line from one roll to the next is connected through a check valve 40, to a steam inlet connection 41 common also to the independent steam supply lines 12 to 15' of the various rolls for a purpose to be hereinafter described. The initial rolls 1 and 6, of course, need not have the drain connections as are shown for the succeeding rolls since they receive high pressure steam and no great amount of condensation will take place.

It is sometimes desirable to have drying apparatus of this character operate with greater than atmospheric pressure on the wet end driers and for this purpose the exhaust lines 26 and 27 from the wet end cylinders are provided with connections 43 which are each connected to the condensation header or manifold 28 through valve 43, sediment separator 44, trap 45 and valve 43', while through by-passes 46 in which valves 47 are located, the exhaust from the wet end cylinders may be opened directly to the condensation header 28 to allow a drop in pressure in the end cylinders or over all the cylinders of one or both series. To accomplish this purpose the valves 47 will be regulated. For the purpose of determining steam pressures and testing the relative differential pressures between inlets and outlets of each drier, etc., suitable steam gauge connections such as are indicated at 48 may be provided. With my arrangement, it will of course, be readily possible to connect two steam gauges in the lines entering and leaving each cylinder to note the differential pressures, or one compound steam gauge may be connected across the line and used for the purpose.

From the foregoing it will be apparent that steam entering the manifold or header 16 from any source will be supplied through pipes 11 and 11' to the end cylinders or rolls or units 1 and 6 at the dry ends of their respective series and will pass successively through each cylinder of the respective series to the last cylinder at the wet end from whence it will be discharged into the exhaust or condensation manifold 28. During this time condensation will be removed from each cylinder, roll or unit and from the connecting lines 18 to 25 inclusive through the strainers 130

38, trap valves 39 and lines 29 to 32' inclusive.

In order that the rolls may be maintained at consecutively lower temperatures from the dry end to the wet end, the exhaust steam from each cylinder is utilized in the succeeding cylinders, and in order that the steam supplied to each succeeding cylinder may be kept constant to maintain the temperature, each cylinder, roll or unit, except the initial 5 rolls or units 1 and 6, is provided with what I may term a differential valve 49 which may be of any suitable type, but preferably adjustable, arranged to admit additional steam to the steam inlet connection from the manifold 16 through the individual or independent connections 12, 12', 13, 13', 14, 14', 15 and 15', should the steam supplied such cylinder from its next preceding cylinder fall below a predetermined quantity or quality. 10 Thus each differential valve controls the steam admitted to its respective cylinder from the independent steam supply of such cylinder and, in order to control the proper differential pressures between succeeding cylinder, 15 pipes 50, 51, 52, 53, 54, 55, 56 and 57 connect the pressure regulating mechanism of the differential valves with individual or independent connections 11, 11' etc. of the next 20 preceding cylinder or unit. The pressure of the steam in the several units of each series may be controlled in numerous ways with proper connections between the units or by different adjustments of the differential 25 valves and resort may be had to various other means for equivalent control. As these differential valves are old, well known and form, per se, no part of my invention, they are not further described herein.

It will, of course, be apparent that should 30 there be not sufficient steam flowing from one cylinder to another through the series of exhaust connections to heat the cylinder to a predetermined temperature, an additional quantity will be admitted through the independent connections 12, 12', 13, 13', etc., until the temperature or pressure desired in such unit has been reached. The check valves 40 will prevent steam entering from the connections 12, 12', etc., from passing back into the exhaust line from the preceding unit.

The valves 49 may, as has been stated, be of any suitable type operable by pressure or by the thermal coefficients of the various units, 45 although they are preferably adjustable in order that successive differential valves from the dry to the wet ends may be set to open at successively lower differential pressures or temperatures between the steam entering 50 through the series exhaust connections and the independent or individual unit steam supply connections for the maintenance of a predetermined temperature within each and over all the respective units.

55 Dry steam, whether saturated or super-

heated, may be received from any convenient source, of course depending on the conditions at such source, into the manifold 16 and will enter the dry end cylinders at its initial pressure and temperature. Preferably a condenser system is attached to the exhaust manifold 28 through a pipe connection 60 65 70 75 80 85 90 95 100 105 110 115 120 125 130 connection 63, as will be more particularly described hereinafter, in order to create a differential pressure between such exhaust line and the steam manifold 16. The valves 34 will remain open until condensation and non-condensable gases contained in the manifold and piping connected thereto have been exhausted or until steam begins to pass them. At this point they are so constructed and arranged that they will close and prevent passage of steam, opening from time to time as water and air of a less temperature than steam accumulate. The steam entering the dry end cylinders will pass through such cylinders and through the respective exhaust lines to the next succeeding cylinders through the check valves 40 and connections 41, thence through the cylinders and out the succeeding exhaust lines to the next succeeding cylinders, etc. Condensation in the exhaust lines or in the steam as it passes from one cylinder to another will be trapped in the pipe adjacent the next succeeding cylinder, will pass through the sediment separator or strainer 38 into the valve designated 39 and thence to the exhaust manifold 28. The traps 39 will, of course, operate in the same manner as traps 34, for they will close immediately upon the entrance of steam therein. A connection may be made between a lower bottom portion of the end walls of the cylinders (which are usually rotary) to the strainers or separators 38 for the removal of condensation from the interior of the cylinders if desired.

Assuming that it is desired to maintain a pressure ratio in arithmetic progression from the dry to the wet end in each series of cylinders, i. e., a ratio of 6#, 5#, 4#, 3#, 2#, any pressure regulator in the line 16 may be set for the initial pressure to enter the dry end cylinders. Exhaust steam passing from the dry end will tend to maintain a substantially lower pressure and temperature within succeeding cylinders, but, should the exhaust steam from any preceding cylinder be insufficient to maintain the pressure and temperature desired within the succeeding cylinder or cylinders as determined by the setting of the differential valves 49, the valves are so arranged and constructed that they will operate to admit steam through the independent or individual connections 12, 12', 13, 13', 14, 14', 15 and 15' (as necessary) until the desired temperature or pressure for which they have been set has been attained. The by-passes 46 may be opened up, of course, to

- any degree to vary the pressure conditions within the wet end cylinders as may be desirable, i. e. above or below atmospheric, and the differential valves 49 may be adjusted 5 in the usual manner for maintenance of consecutive or varying differential pressures in the various rolls of each series. The bypasses render it possible to maintain greater than atmospheric pressure on each wet end 10 drier and waste of steam is prevented by the globe valves 47 in the by-passes. A circulation of steam through the wet end drier may thus be maintained by partially opening the globe valve on each by-pass.
- 15 As hereinbefore noted, any suitable condensation system may be used in connection with the drying roll system as desired, although I prefer the system shown in Fig. 3, now to be described.
- 20 The condensation line 63 is connected through a T 64 to the top of a condenser tank 65, preferably made of black steel and adapted to stand a gauge working pressure of 100 pounds according to the A. S. M. E. 25 code. This tank has two openings in the top of the shell, one providing an inlet from the T connection 64, the other providing an outlet or vent 66. A manhole and cover 67 may be provided at one end for cleaning the 30 tank, as is usual in the art, and provision is also made for an inlet at 68 also in the end of the tank and two outlets in the bottom of the tank, one a drain 69 and the other an outlet 70 for the removal of the accumulated 35 condensate. Each outlet is suitably coupled to the shell of the tank, as will be understood.
- The opposite run side of the T 64 is connected to a second T 71 connected at its opposite opening to a condenser feed spray line 40 72 having a by-pass 73, hand valves 74, 76, 77, and a pressure regulating valve 78. While the side outlet of the T 71 is connected through a hand valve 79 and check valve 80 in a bypass line 81 to a steam line 82.
- 45 A tilt valve trap 83 such as that described in the patent to Oswald, 1,251,092 of December 25, 1917, or that to Burke, 1,242,917 of October 16, 1917, is suitably arranged to pump the water from the tank 65 through the 50 outlet 70 and lines 84 and 85 to a feed water heater hotwell or the like. This tilt valve trap will not be described since it is amply described in the aforementioned patents. The steam for operating the valve trap is supplied through line 86 and the exhaust steam from the valve trap passes through line 87 to lines 82 and 88; from line 82 the greater amount of steam will pass through the line 89, through the inlet 68 to an internal vent 55 91 for condensation thereof, while a small amount of steam under the pressure of the line 87 will be carried through line 88 connected to the pressure regulating valve 78 for control of the condensing water supply 60 65 entering through the pipe 75.

The coupling in the end of the tank connected through opening 68 is fitted with an internal pipe 92 having six or any other suitable number of preferably $\frac{3}{4}$ inch holes drilled near one end adjacent to and behind the opening in the vent pipe 91, while at its other end this pipe 92 is supplied with a T 93 having a discharge opening 94 and its side outlet 95 is provided with a short piece of pipe or the like for the support of the pipe 92 upon the bottom of the tank. This, as will be obvious, provides a substantially silent vent condensation means as the steam vented from the tilt valve trap will force the water accumulated ahead of the vent 91 out of the 70 end of the tank and thereby draw in water 75 through the holes behind it.

The tilt three valve trap 83 is of suitable size dependent upon the conditions for which it is required and should be mounted at least 80 one foot above the floor, while the yoke of the trap should be not less than two feet below the bottom of the shell of the tank. The vent line 87 is preferably provided with an auxiliary vent line connection 96 and provided with a hand valve 97 adapted to be utilized for venting the steam from the tilt valve when the vacuum pump to be herein-after described is not operating. Hand and check valves 98 and 99 respectively are placed 85 in the line 87 for this purpose. A sediment trap 100 and a sediment blow-off valve 101 are provided in the line 84 and suitable other valves are connected in the various lines for 90 obvious purposes.

A vacuum pump 102 is connected through lines 103, 104, 106, valve 107 and outlet connection 66 to the top of the tank in order to maintain a pressure within said tank below atmosphere and to maintain a differential pressure between the steam conduit 16 and the condensation manifold 28. A water supply line 108 having a by-pass 109 is connected as at 110 to the intake 103 of the vacuum pump in order to form a seal for the pumping mechanisms as is usual, and is regulated through a regulating valve 111 operated by the pressure in line 104 for the purpose of which it is connected through the line 112 thereto. The discharge end of the vacuum pump is connected to a water discharge line 113 and an air vent 114.

In operation the tilt valve trap will receive water from the tank 65 and discharge it to the hotwell feed water heater or boiler or the like by means of the live steam supplied thereto through the pipe 86. When the trap returns to its falling position the steam utilized therein will be vented to the line 87, will cause the regulating valve to open and supply condensing water from the line 75 for condensing the steam discharge through the bypass 81 when opened and any steam flowing from the line 63. Most of the steam vented 115 120 125 130

from the tilt trap will be condensed in the internal vent pipe 92. The heat of condensation will be conserved and the tank 65 maintained under pressure at or less than atmospheric pressure by means of the vacuum pump which will not receive any of the condensation so that a constant differential pressure is maintained between the various units of the drying rolls and the condensation system. This arrangement will attain a principal object of the invention, viz, to induce a rapid and continuous circulation of steam in one or more series of steam circuits with a complete separation of condensation from the steam. The air and condensation are quickly discharged into the tank and a substantially constant differential pressure is maintained. The system is at once simple and efficient and may be adapted for any variety of uses, as will be apparent.

Many variations and modifications of construction and operation may be made, as, for instance, any number of units of the same or varying temperatures may be connected in series or in parallel series within the broader aspects of my invention, and for this reason I do not desire to be limited to the details of construction or arrangement, but only by the spirit of the invention and the scope of the appended claims.

I claim:

1. In combination, a series of drying chambers in number greater than two, a source of high temperature high pressure vapor supply connected to each of said chambers, direct vapor flow connections between a plurality of said chambers, means for maintaining a constant differential pressure between successive chambers of said series, and means for removing condensed vapors from said chambers.

2. In combination, a series of drying chambers in number greater than two, a source of high temperature high pressure vapor supply connected to said chambers, direct vapor flow connections between a plurality of said chambers, means for maintaining a constant differential pressure between successive chambers, means for removing condensed vapors from said chambers, and means for maintaining a differential pressure between said vapor supply source and said condensed vapor removal means.

3. In combination, a series of heat conducting elements, a source of heat supply common to all of said elements, and means including direct exhaust connections between successive elements for maintaining a constant temperature differential between successive elements in decreasing ratio from one end of said series to the other.

4. In combination, a series of heat conducting elements, a common heat source, and means including direct exhaust connections

between successive elements for maintaining a predetermined and constant temperature differential between successive elements in decreasing ratio from one end of said series to the other.

5. In a drying system in combination, a series of material drying cylinders in number greater than two, means for supplying heat to each of said cylinders in succession from the outlet of one to the inlet of the next, and means for supplying heat to each of said cylinders individually.

6. In a drying system in combination, a series of material drying cylinders in number greater than two, means for supplying a heated medium from one to another of each of said cylinders in consecutive succession, means for supplying a heated medium to each of said cylinders individually, and means dependent upon a characteristic of the medium from one of said supply means for varying the supply of medium from the other.

7. In a drying system in combination, a series of cylinders adapted to be heated interiorly, means for supplying a heating medium to each cylinder independently, means for supplying heating medium to a plurality of said cylinders in number greater than two in succession, means for removing condensate from each cylinder and means for predetermined the supply of heating medium entering each of said plurality of cylinders from one of said supplying means in accordance with a characteristic of the heating medium supplied by the other supply means.

8. In a drying system in combination, a series of hollow cylinders greater than three adapted to receive steam, and means including an exhaust connection from each cylinder to its adjacent cylinder in the same order for maintaining a substantially constant differential temperature between consecutive cylinders.

9. In a drying system in combination, consecutively arranged drying cylinders to be steam heated, a steam supply manifold, steam connections from said manifold to each of said cylinders, means to exhaust steam from each preceding cylinder to each succeeding cylinder, means for maintaining a predetermined temperature in each of said cylinders, and means for removing condensation from each exhaust means.

10. In a drying system in combination, a plurality of consecutively arranged drying units adapted to be steam heated, a steam supply manifold common to all of said units, means for predetermined the pressure of steam supplied to said manifold, independent connections from said manifold to each of said units, connections from each of said units to the next succeeding unit to supply exhaust steam therefrom to the next succeeding unit, and regulating means in con-

- nection with each unit, except an end unit, for controlling the amount of steam supplied thereto through its independent connection in accordance with its temperature characteristic. 5
11. In a drying system in combination, a plurality of consecutively arranged drying units adapted to be steam heated, a steam supply manifold common to all of said units, independent connections from said manifold to each of said units, connections from each of said units to the next succeeding unit for supplying exhaust steam from the preceding unit to the succeeding unit, and means in connection with each unit except an end unit for controlling the volume of steam supplied thereto through its independent connection in accordance with the temperature characteristic of the succeeding unit. 10
12. In a drying system in combination, a plurality of consecutively arranged drying cylinders adapted to be steam heated, a steam supply manifold common to all of said cylinders, independent connections from said manifold to each of said units, connections from each of said cylinders to the next succeeding cylinder for supplying exhaust steam from the preceding unit to the succeeding cylinder, and means for removing condensation from each of said units except said end unit. 15
13. In a drying system in combination, a series of steam heated drying roll units, including a high pressure unit, a low pressure unit and intermediate pressure units, a source of high pressure steam, a direct connection from said source to said high pressure unit, connections for passage of exhaust steam from successively higher to successively lower pressure units, and auxiliary connections from said source to each of the units below said high pressure unit, and means for controlling the steam supplied by each of said auxiliary connections. 20
14. In a drying system in combination, a series of steam heated drying roll units, including a high pressure unit, a low pressure unit and intermediate pressure units, a source of high pressure steam, a direct connection from said source to said high pressure unit, connections for passage of exhaust steam from successively higher to successively lower pressure units, and auxiliary connections from said source to each of the units below said high pressure unit, and means for automatically controlling the steam supplied by each of the auxiliary connections to their respective units in predetermined quantities. 25
15. In a drying system in combination, a series of steam heated drying units including a high pressure unit, a low pressure unit and intermediate pressure units, a source of high pressure steam, a direct connection from said source to said high pressure unit, connections for passage of exhaust steam from successively higher to successively lower pressure units, and auxiliary connections from said source to each of the units below said high pressure unit, and means for controlling the steam supplied by each of the auxiliary connections to their respective units in accordance with the temperature characteristic of the steam exhausted to the unit to which it is connected, from the preceding unit. 30
16. In a drying system in combination, a series of steam heated drying units including a high, a low and an intermediate pressure unit, a manifold common to a plurality of said units, a source of steam supply connected to said manifold, independent connections from said manifold to each of said units, series connections between each of said units for the passage of exhaust steam from successively higher to successively lower pressure units, means for automatically regulating the steam supplied to each unit below said high pressure unit in accordance with a predetermined characteristic in proportion to the temperature of such unit, and means for removing condensate from intermediate and low pressure units. 35
17. In combination, a plurality of series of drying rolls including high, intermediate and low temperature rolls in each series, means for supplying a high temperature condensable vapor to each of said rolls in each series, means connecting the rolls of each series in series for supplying exhaust vapor from successively higher to successively lower temperature rolls, and means for maintaining a predetermined and constant temperature in each roll of each series below said high pressure rolls. 40
18. In combination, a plurality of series of drying rolls including high, intermediate and low temperature rolls in each series, means for supplying a high temperature condensable vapor to each of said rolls in each series, means connecting the rolls of each series in series for supplying exhaust vapor from successively higher to successively lower temperature rolls, and means for maintaining a predetermined differential temperature constant between adjacent rolls of each series. 45
19. In a drying system in combination, a plurality of consecutively arranged drying cylinders adapted to be steam heated, said cylinders being in number greater than two, a steam supply manifold common to all of said cylinders, independent connections from said manifold to each of said cylinders, an exhaust connection from each cylinder to the steam inlet of the next succeeding cylinder, a steam trap connected with each cylinder except an end cylinder for removing condensate from the cylinder to which it is connected, and regulating means in connection with each cylinder. 50

cylinder except an end cylinder, for controlling the volume of steam supplied thereto through its independent connection from said manifold in accordance with its temperature characteristic.

In witness of the foregoing I affix my signature.
